UNITED STATES PATENT OFFICE.

CHARLES H. HACKETT, OF WATERLOO, IOWA, ASSIGNOR TO WILBUR W. MARSH, OF WATERLOO, IOWA.

CENTRIFUGAL LIQUID-SEPARATOR.

No. 840,057.

Specification of Letters Patent.

Patented Jan. 1, 1907.

Application filed October 30, 1905. Serial No. 285,081.

To all whom it may concern:

Be it known that I, CHARLES H. HACKETT, a citizen of the United States of America, and a resident of Waterloo, Blackhawk county, Iowa, have invented certain new and useful Improvements in Centrifugal Liquid-Separators, of which the following is a specification.

My invention relates to improvements in centrifugal liquid-separators; and the object of my improvement is to provide an exit-tube for the newly-separated lighter constituent of the liquid which shall be so capable of adjustment that its inner end may be brought nearer to or farther away from the axis of the separator-bowl, as desired, while the outer or true exit end of said tube remains fixed in one position. This object I have accomplished by the means which are hereinafter described and claimed and which are illustrated in the accompanying drawings, in which—

Figure 1 is a vertical section of a separator-bowl along the line of its axis containing my improved exit-tube for the lighter separated constituent of the liquid. Fig. 2 is a detail view of said tube, and Fig. 3 is a horizontal section of said bowl along the line xx of Fig. 1.

Similar reference characters refer to similar parts throughout the several views.

I have depicted a separator-bowl g of a familiar type, having a cover whose ring-shaped top f has a central opening for the reception of a clamping-shaft k . The latter has an expanded body at the top containing a chamber communicating by means of an opening in with the interior of the bowl for the entrance to the bowl of the liquid to be separated. The lower end of said shaft k is provided with a thread to fit into a threaded opening in the center of the upper surface of the bottom of the bowl. n is an exit for the heavier separated constituent of the liquid. I have shown a liner of a simple type within said bowl composed of standards c , connecting circular top and bottom plates b and h , respectively. The top plate b has an opening near the usual outer dividing-point of the lighter and heavier constituents of the liquid, and in this opening a vertical tube a is fixed in such a manner that its upper end projects above said plate and extends into and to the top of a registering opening in the ring on the cover of the separator-bowl. The

lower end of said exit-tube a extends downwardly into the interior of the bowl, and a short distance below the plate b said tube is cutaway in such a manner along a plane passing vertically along its axis as to leave the vertical open side of the remaining half directed toward the axis of the separator-bowl and parallel therewith. This tube is open throughout its extent and affords means of unobstructed communication between the interior and exterior of the bowl for the exit of the separated lighter constituent of the liquid.

In order to shift the lower end of the tube a toward the axis of the bowl, I have placed means therefor adjacent to the outer portion of the lower end of its trough-shaped part, described as follows: On a standard c adjacent to the tube a is mounted an interiorly-threaded bearing-lug d , with axis at right angles to the lower end of said tube. Within this bearing works a screw e , having a slot across the face of its outer end, whereby it may be turned by the use of a screw-driver. The inner end of said screw e impinges against the outer side of the lower end of the trough of said tube a and when said screw is turned in one direction pushes inward the elastic trough to a point nearer the axis of the separator-bowl and when turned back allows the lower end of said trough to spring back to its former position to any required degree within its compass of movement. When the lower end of the trough of the tube a is pushed inward nearer the axis of the bowl, it is in a position to skim a liquid such as milk where the milk contains a high degree or proportion of cream, and when the tube is allowed to move to an adjustment farther out it is in position to skim when the milk contains a less proportion of cream.

Attention is particularly called to the fact that the upper end and proper exit of the tube a is in a fixed position within the separator-bowl, being rigidly connected to the upper plate b of the liner, as well as being held fixedly within the inclosing opening in the top ring of the cover f . The result is that the delivery of the separated lighter constituent of the liquid is always at a single place, which prevents the necessity for constant change of the receiving-pan whenever the lower end of the tube is shifted. In other words, the shifting of the lower end of the

tube, while permitting adjustment to skim milk according to the relative proportion of cream contained therein, does not alter the direction of delivery or the position of the 5 exit.

Having described my invention, what I claim as new, and desire to secure by Letters Patent, is—

1. In a centrifugal liquid-separator bowl, 10 an exit-tube for the lighter separated constituent of the liquid whose upper end is in a fixed position relative to the axis of the bowl, and whose lower end is adjustable toward and from said axis, and means for adjusting 15 the lower end of said tube toward and away from said axis.
2. In a centrifugal liquid-separator bowl, 15 an exit-tube for the lighter separated con-

stituent of the liquid whose upper end is in a fixed position relative to the axis of the bowl, 20 the lower end of said tube being opened into the shape of a trough on the side nearest said axis and adjustable relatively toward and from said axis, a liner within said bowl, a lug having an interiorly-threaded bearing 25 affixed to said liner, a screw in said bearing adapted to contact with the lower end of said exit-tube and adjust it to a greater or less distance from the axis of said bowl.

Signed at Waterloo, Iowa, this 10th day of 30 October, 1905.

CHARLES H. HACKETT.
